SIGN

John M. Diehl, 5729 Elder Place, Madison, Wis.

Filed June 4, 1964, Ser. No. 80,290

Term of patent 3½ years

(Cl. D1—12)

FIG. 1

FIG. 2

FIG. 3

FIG. 4

FIGURE 1 is a front perspective view of a sign embodying my new design;

FIGURE 2 is a top plan view thereof;

FIGURE 3 is a front elevational view thereof; and

FIGURE 4 is a rear perspective view thereof.

The dominant features of my design reside in the portions shown in full lines, it being understood that the fragmentary broken line representation of an automobile is for purposes of illustration only.

I claim:

The ornamental design for a sign, as shown and described.
